COMBINED DISPENSER AND RECEPTACLE
FOR CLEANSING DENTURES AND OTHER
ARTICLES

Harry Cohn, Brooklyn, N. Y.

Application July 12, 1950, Serial No. 173,321

1 Claim. (Cl. 222—117)

1

This invention relates to a device for cleaning dentures and other articles, and more particularly to a combined dispenser and receptacle for dispensing a controlled amount of finely divided solid cleansing material into the receptacle into which may be placed the denture or other article to be cleansed.

One object of this invention is to provide a combined dispenser and receptacle which is simple in construction, can readily be fabricated so that it is inexpensive to make, which functions to deliver a controlled amount of finely divided solid cleansing material into the receptacle and in which the receptacle is so positioned and constructed that liquid and the denture or other article can readily be placed therein.

Another object is to provide such combined dispenser and receptacle which in use permits of the ready agitation of the contents of the receptacle to effect efficient cleansing of the denture.

Other objects and advantages of this invention will be apparent from the following detailed description thereof.

In the preferred embodiment illustrated on the drawing the invention is shown incorporated in a combined dispenser and receptacle for use in cleaning dentures and the present description will be confined to the present illustrated embodiment of the invention. It will be understood, however, that the novel features and improvements are susceptible to other applications, such, for example, as the cleansing or other treatment of other articles, particularly relatively small household articles. Hence, the scope of this invention is not confined to the embodiment herein described.

In the accompanying drawing forming part of this specification and showing, for purposes of exemplification, a preferred form of this invention, without limiting the claimed invention to such illustrative instance:

Figure 1 is a perspective view of a combined dispenser and receptacle embodying my invention;

Figure 2 is a vertical section taken in a plane passing through line 2—2 of Figure 1; and

Figure 3 is a horizontal section taken in a plane passing through line 3—3 of Figure 2.

In the drawing 10 indicates a combined dispenser and receptacle comprising a vertically disposed supporting member 11 to the top of which is secured a dispenser 12 and to the base of which is secured a receptacle 13. Receptacle 13 is disposed directly below the dispenser 12 with a space therebetween of sufficient extent to permit the

device to be moved so that a faucet or other source of water is disposed in this space to supply water to the receptacle 13. The combined dispenser and receptacle may be made of any suitable material, such as plastic or metal; a plastic, such, for example, as polystyrene, polyethylene, "Beetleware," "Lucite," etc., is the preferred construction material.

Supporting member 11, handle 14, dispenser container 15 and receptacle 13 may be of one piece integral construction, or, if desired, container 15 and receptacle 13 may be formed as separate units and suitably secured to the top and bottom of the supporting member 11. Handle 14 may be omitted, if desired, and the device held by supporting member 11.

Dispenser 12 desirably comprises a cylindrical container 15, which, as above indicated, may be molded so that cylindrical side wall 16 is integral with base 17. The base 17 is provided with a plurality of small openings 18 disposed in a confined locality of the base, as shown in Figure 3. In the embodiment shown in the drawing three closely spaced openings are used. It will be understood, however, that any desired number of openings may be employed to dispense the desired amount of material as will be more fully explained hereinafter.

A cover 19 having a flange 20 closes the top of container 15. This cover 19 is provided with an opening 21 of a size such that a spindle 22 passes therethrough leaving a small clearance permitting the free rotation of spindle 22 in the opening 21 of cover 19.

Suitably secured to the lower end of spindle 22 is a discharge plate 23; spindle 22 and plate 23 may be of one piece cast construction, if desired. In the embodiment of the invention shown in Figure 2 the discharge plate 23 is shaped to provide a concave area 24 in the face or top portion thereof. The base of this concave area is provided with a plurality of openings 25. Three such openings are shown in the embodiment of the invention disclosed in the drawing, although it will be understood any desired number of such openings may be used. Desirably, the upper portion of spindle 22 is knurled, as indicated at 26, and is of polygonal shape permitting the ready rotation of the plate 23 within container 15 by simply grasping the knurled head 26 with the fingers and turning the spindle 22.

While the construction hereinabove described and shown in the drawing involves a cylindrical receptacle 13 and a cylindrical container 15, the receptacle 13 being disposed just below the con-

5 tainer 15, it will be understood the shape of this container and receptacle may be varied as desired. Thus, receptacle 13 may be polygonal shape instead of the cylindrical shape shown. Likewise, container 15 may be of any desired shape permitting the free rotation of a discharge plate therein.

In use, cover 19 is removed from container 15 the spindle 22 permitting the ready removal of this cover without disturbing the spindle or the plate 23 carried thereby. Finely divided solid matter, such as the denture cleansers now available commercially, solid detergent, etc. is then poured into container 13 on top of plate 23, this plate being positioned so that the openings 25 therein do not register with the openings 18 in the base of container 15. In this position of the parts, no flow of the finely divided solid matter takes place through the discharge plate 23, but the material rests on the plate filling the concavity 24 and the space above plate 23. After the desired amount of finely divided solid material is placed in container 15 the cover 20 is replaced. Container 15 desirably is of a capacity to hold enough cleanser to permit use of the device for say a week or longer without refilling the container 15.

When it is desired to cleanse the denture it is placed in receptacle 13 and the combined dispenser and receptacle positioned so that the receptacle 13 receives water, say from a faucet. Before or after the introduction of the water into receptacle 13 the disc or discharge plate 23 is given one or more revolutions by the user grasping the head 26 and turning same. This will cause discharge of a controlled amount of solid detergent through the openings 25, when these openings register with the openings 18. The size and number of these openings, the number of revolutions, and speed of rotation control the amount of cleanser dispensed into the receptacle 13. The parts desirably are so proportioned that one revolution of discharge plate 23 dispenses just the right amount of denture cleanser to effect efficient cleansing of a denture. After the denture cleanser, denture and water are placed in receptacle 13 the device is moved to effect agitation of the contents of the receptacle 13 thus thoroughly cleaning the denture therein.

It will be noted this invention provides a combined dispenser and receptacle which is simple in construction, which can readily be fabricated and is therefore inexpensive to manufacture, which functions to deliver a controlled amount of a finely divided solid cleansing material to the receptacle, which in use permits of the ready agitation of the contents of the receptacle to effect

5 efficient cleansing of the denture disposed in the receptacle and in which the receptacle is so positioned and constructed that water or other liquid, such as tap water, and the denture can readily be placed therein.

10 Since certain changes may be made in the above described combined dispenser and receptacle and different embodiments of the invention could be made without departing from the scope thereof, it is intended that all matter contained in the above description or shown in the accompanying drawing shall be interpreted as illustrative and not in a limiting sense.

What is claimed is:

- 15 A combined dispenser and receptacle for use in cleaning dentures and other articles, comprising, in combination, a vertically extending support, a handle on one side of said support, a dispenser for finely divided solid material secured to the upper end of said support on the other side thereof, a receptacle secured to the lower end of said support on the said other side thereof and disposed in substantially longitudinal alignment with said dispenser in position to receive finely divided solid material discharged by said dispenser, said receptacle being spaced from said dispenser so that the combined dispenser and receptacle can be positioned with the receptacle beneath the discharge spout of a water faucet to receive water therefrom, said dispenser comprising 20 a container having openings in the base thereof, a discharge plate rotatably mounted in said container, said discharge plate having the top surface thereof of concave shape and having openings in the lowermost portion of the concavity which openings upon rotation of said plate are adapted to register with the openings in the base of said container, a cover for said container, said cover having a centrally disposed opening 25 therein, and a spindle extending from said discharge plate through the opening in said cover, said spindle having an extending portion arranged to be engaged by the user to effect rotation of said discharge plate.
